RADIO CONTROL DEVICE

Adolf Spöttel, Berlin, Germany, assignor to Tele-funken Gesellschaft für Drahtlose Telegraphie m. b. H., Berlin, Germany, a corporation of Germany

Application February 7, 1935, Serial No. 5,377
In Germany February 7, 1934

5 Claims. (Cl. 250—40)

Scale arrangements are known in which the printed station names are arranged in accordance with certain viewpoints, for instance according to the alphabet, or to the respective country, but they are not arranged in accordance with their transmitter frequencies. Marking points are assigned to these station names by which the tuning is indicated. The tuning therefore is carried out in such a manner that the desired station is looked up in the station list which by means of the arrangement above mentioned can be easily accomplished, whereafter the tuning knob is to be turned until the tuning to the respective station is indicated. Hereby it may rather easily happen that this marking be overlooked and that the tuning means must be moved several times back and forth before the accomplished tuning is recognized.

In accordance with the invention these difficulties are overcome in that a full automatic tuning is provided in such a manner that simply the bringing into coincidence of a pointer movable in front of the station table with the respective station name effects the tuning. For a better understanding of the invention reference is made to the accompanying drawing, in which;

Fig. 1 is a front view, partly diagrammatic, of one embodiment of the invention and

Fig. 2 is an enlarged view of an adjustable slide employed and its cooperating adjusting members.

Fig. 1 of the accompanying drawing shows an example of a construction of the setting arrangement in accordance with the invention. Herein 1 is the shaft on which the tuning means is mounted. In the present case it is a variable condenser. On shaft 1 a rope drum 2 is likewise fixedly mounted over which a rope 3 leads across various guide rollers to a fixed point 4 of the receiver chassis. A part 5, for instance a pin, is fixedly secured to rope 3. 6 designates a table of station names over which a pointer 7 moves. This pointer is fastened to a plate 8 and can be moved therewith from the outside. The plate 8 carries four rollers 9 between which the rope 3 passes with two parallel pieces of a loop formed by suitable guiding by means of rollers 10. In the center of the disk 8 a lever 11 is rotatably mounted and whose ends carry rollers 12. The lever is so formed that it does not touch the rope 3 in the position shown, while when turned at 90° from this position it laterally deviates the rope as shown by the dash line. The rope 3 will therefore be shortened and will be wound off the rope drum 2 against the action of spring 13, by a rotation of lever 11 which likewise can be carried

out from the outside. The arrangement is such that the condenser is thereby drawn into one of its end positions.

A movement of the pointer with the plate 8 is not prevented by this tensioning of the rope, in spite thereof the pointer 7 can be moved in front of the scale 6. On the other hand, the tension of the rope 3 will not be changed by the movement of the pointer 7.

A second rope which extends across suitable guide rollers 15 and rotates a disk 16 is connected to plate 8. The disk 16 is so constructed that it presents radially directed notches of various depths. The entire arrangement is such that the part 5 cooperates with the notches in such a way that a movement of the part 5 towards the right is prevented up to the end position by the base of the notches in the disk 16. The notches have such a depth that the variable condenser will be just retracted by the spring 13 into the position of tuning of the station indicated by the pointer 7.

Fig. 2 shows further details. Herein 17 is the front wall of the receiver casing having a slot 18 therein. Through this slot there reaches an arm 19 secured to the disk 8 and a further lever 20 pivoted at 21 to the disk 8 and having at its other end a circular rack or toothed portion 22. This rack 22 cooperates with a gear 23 fixedly secured to the lever 11. The scale is to be considered as positioned alongside the slot 18, and the pointer 7 moves over the said scale.

The device is arranged in such manner that the plate 8 with the pointer thereon can only be moved when the lever 20 is pressed downwards so that the rope 3 is tensioned by the lever 11. Hence the stop 5 is drawn towards the left and consequently no longer in contact with the disk 16. Now by moving the pointer 7 by means of the arm 19 the said pointer can be brought into coincidence with the desired station name, whereby at the same time the disk 16 will be so turned that a correspondingly deep notch will be opposite the stop 5. Upon releasing the lever 20 the stop 5 will be moved up to the bottom of the notch and thus permit a displacement of the tuning means by means of the spring 13 to the desired tuning position.

A vernier or more accurate setting can be obtained by means of a fine adjustment. To this end an eccentrically mounted disk 24 may serve, and which bends out in a lateral direction the rope 3 between the guide rollers 25.

The figures simply serve as an example and to elucidate the inventive idea. The construction may obviously deviate in many points from that

described. Thus for instance, the tensioning of the spring 13 may be obtained by a displacement of the point 4 or of the roller 10 with respect to the chassis. The disk 16 is not required to be 5 rotatably mounted, it may have a rectangular shape and then be displaced by the rope 14.

I claim:

1. Means for adjusting a tuning device comprising in combination, means for rotating said device to an end position in one direction, a flexible member secured to said device one end of said flexible member being fixed, means for moving an intermediate portion of said flexible member to rotate said device in the opposite direction, 10 a stop member connected to said flexible member, and an adjustable member having a plurality of projecting portions of different lengths arranged to engage said stop member.
2. Means for adjusting a tuning device to a tuning 20 position comprising the combination of a scale, a pointer movable along said scale, means for rotating said tuning device in one direction, a stop member consisting of a flat disc having a plurality of substantially radially arranged 25 notches of different depths, means connecting said stop member and pointer, and means for rotating said tuning device in the opposite direction to the tuning position comprising a flexible member having a portion arranged to engage the different notched portions of said stop member.
3. A device according to claim 2 in which said flexible member extends past said pointer and has 30

one end secured in fixed position and a rotatable member mounted adjacent said pointer adapted to engage and bend said flexible member.

4. Means for adjusting a tuning device comprising the combination of a scale, a slide, a pointer secured to said slide and movable along said scale, means for rotating said tuning device in one direction, an adjustable stop member, a flexible member connected to said tuning device to rotate it in the opposite direction, a stop carried by said flexible member and engageable with said stop member, a member mounted on said slide and arranged to actuate said flexible member and a vernier adjusting member mounted between said tuning device and stop member arranged to engage and bend said flexible member. 10 15

5. Means for adjusting a tuning device comprising the combination of a panel having a slot therein, a slide positioned behind said panel and having a handle portion projecting through said slot, means for rotating said tuning device in one direction and means for rotating said device in the opposite direction comprising a flexible member having one end connected to said device and its other end secured in a fixed position, said flexible member having spaced apart parallel portions adjacent said slide, a member pivoted to said slide and arranged to flex at least one of said parallel portions and a control member projecting through said slot and connected to actuate said 20 25 30 pivoted member.

ADOLF SPÖTTEL.
